UNITED STATES PATENT OFFICE

RALPH PRATER, OF OAK PARK, ILLINOIS

GRINDER

Application filed August 21, 1929. Serial No. 387,518.

My invention relates particularly to grinders such as are used in grinding cereals or farm stock feed although not limited to this use alone.

5 The main object of the invention resides in the provision of means whereby the rate of flow or feed of material into the grinder is maintained extremely uniform, and whereby the feed of the material may be at an extremely slow rate without clogging and consequent interruption of the feed or interference with the uniformity of the feed, due provision being preferably made for adjustment of the rate of feed.

10 With this object in view my invention consists in certain features of novelty in the construction, combination, and arrangement of parts by which the said object and certain other objects hereinafter appearing are effected all as fully described with reference to the accompanying drawings and more particularly pointed out in the appended claims.

In the said drawings—

15 Figure 1 is a side elevation of a grinder embodying my invention with parts broken away and shown in section;

Figure 2 is an end elevation of the same with a part shown in section;

20 Figure 3 is an enlarged partial section on the line 3—3 of Figure 2.

Like characters of reference indicate like parts in the several views.

Referring to the drawings, 1 designates a casing within which extends a revolvable shaft 2 carrying hammers 3 which during rotation of the shaft grind material fed into the casing, the material being discharged through a sizing screen 4 at the bottom of the casing when sufficiently reduced. See Figure 1.

The ends of the casing wall are vertical and one of these is provided with a feed aperture 5 through which material to be ground is fed into the casing, a hopper 6 on the exterior of the casing and secured thereon being arranged for feeding material through this aperture into the casing. See particularly Figures 1 and 3.

25 Detachably secured on the exterior face of the vertical end wall portion of the casing 1

provided with the feed aperture 5, by means of a headed screw 7, is a plate 8 provided with a feed opening 9 overlying the feed aperture 5. See Figures 1, 2 and 3.

Secured on the exterior face of the plate 8 is a pair of vertically extending parallel slides 11 arranged at opposite sides of the feed opening 9. Slidably mounted in these slides, and consequently disposed on the outer face of the plate 8, is a second transversely disposed plate 12 which in its movement in the slides 11 is vertically movable across the feed opening 9 for purposes hereinafter set forth.

The plate 12 is adjustably positioned vertically by means of a manually operable vertical screw crank 13 screwthreaded through a block 14 secured on the upper end of the plate 8 and having at its lower end a bearing engagement with the turned over upper end 70 of the plate 12, as designated at 15. See particularly Figure 3.

An upwardly facing bucket formation 16 is secured on the inner face of the plate 8 and extends about the feed opening 9 of this plate 75 and provides a transversely disposed upwardly extending inclined lip member 17 at the discharge end of the hopper 6 over which material must pass in feeding into the grinder.

The plate 12 provides a downwardly extending lip member adjacently spaced inwardly of the hopper from the lip member 17 under which material must pass in feeding into the grinder.

The plate 12 or lip member and the lip member 17 cooperate to control the flow or feed of material into the grinder, adjustment of the plate 12 downwardly decreasing the flow and adjustment of this plate upwardly increasing the flow.

By reason of the offsetting or horizontal spacing of the lip members a relatively small uniform feed of material into the grinder is provided without decreasing the cross section of any portion of the feed passage to such an extent that the material is liable to clog and interrupt or interfere with the uniformity of the feed. Consequently a uniform feed at relatively slow rate is attainable

In order that an extremely fine or slow rate of feed may be provided the lip member 17 is provided at its upper or feeding edge with a V-shaped indentation 18, so that the lower edge of the plate member may be adjusted considerably below the normal upper edge of the lip member 17 without entirely cutting off the feed.

By reason of the fact that the entire regulating device is carried on the detachable plate 8, it may be removed or installed as a unit, thus providing for convenient interchange with other feed regulating devices if desired.

While I have described and shown the preferred embodiment of my invention I do not wish to be limited to the precise details as changes may readily be made without departing from the spirit of my invention, but having thus described my invention, I claim as new and desire to secure by Letters Patent the following:

1. In a grinder the combination with a feed hopper, of a transversely disposed upwardly extending lip member at the discharge end of said hopper, and a transversely disposed downwardly extending lip member adjacently spaced inwardly of the hopper from said upwardly extending lip member and cooperating therewith to control the feed of material from said hopper, one of said lip members having an indentation at the feeding edge thereof, and means whereby one of said lip members is vertically adjustable with respect to the other lip member to adjust said feed.

2. In a grinder the combination with a feed hopper, of a transversely disposed upwardly extending inclined lip member at the discharge end of said hopper, a transversely disposed downwardly extending vertically movable lip member adjacently spaced inwardly of the hopper from said upwardly extending lip member and cooperating therewith to control the feed of material from said hopper, said upwardly extending lip member having a V-shaped indentation at the upper edge thereof, and means whereby said downwardly extending lip member adjustably positioned in its vertical movement.

3. In a grinder the combination with a grinder casing having a vertical feed apertured wall portion and a hopper on the exterior of said casing for feeding material through said opening, of a plate detachably secured on the exterior face of said vertical wall portion and provided with a feed opening overlying the feed aperture of said wall portion, an upwardly facing bucket formation secured on the inner face of said plate and extending about the feed opening thereof and providing a transversely disposed upwardly extending inclined lip member at the discharge end of said hopper and provided with a V-shaped indentation at its upper

edge, a second plate disposed correspondingly with said first mentioned plate and carried on the outer face thereof for vertical movement with respect thereto across the feed opening thereof and forming a downwardly extending lip member adjacently spaced inwardly of the hopper from said upwardly extending lip member, and vertically arranged screw means carried with said first mentioned plate for vertically adjusting said second plate in its said vertical movement.

In witness whereof I hereunto affix my signature this 12th day of August, 1929.
